PUMP

Philip Lane Scott, Chicago, Ill., assignor to Super
Diesel Tractor Corporation, La Porte, Ind., a
corporation of New York

Application August 7, 1935, Serial No. 35,108

1 Claim. (Cl. 123—139)

This invention relates to fluid pumps and particularly liquid fuel pumps of the type used in internal combustion engines for delivering liquid fuel to an atomizing valve, although it is not limited to pumps of this type. One object of my invention is to provide a simple means of changing the delivery characteristic or flow rate of the pump without altering the shape of the driving cam.

10 Other objects will appear from time to time throughout the specification and claim.

The invention is illustrated more or less diagrammatically in the accompanying drawing wherein:

15 Figure 1 is a vertical section through a cam driven fuel pump;

Figure 2 is a plan view of the adjusting structure including a partial section along 2—2 of Figure 1 of the pump housing;

20 Figure 3 is a graph showing a certain pump delivery characteristic; and

Figure 4 is a graph showing another pump delivery characteristic.

Like numerals refer to like parts throughout.

25 As shown in the drawing, 1 is a pump base supporting a cam shaft 2 carrying a series of cams, one of which is shown 3. 4 is a pump body adjustably mounted on the base 1 and locked in any desired position by the cap screws 5, 5 which are inserted through the slots 5a, 5a. Mounted within the pump body is a slider 6, adapted to slide within the bore 7. Upon the lower end of the slider is a roller 8, mounted upon a pin 9. Within the body 4 is a barrel 10 screwthreaded into the body. Within the barrel 10 is a plunger 11 adapted to reciprocate therein. The plunger and slider are spring returned by means of the spring 12 acting on the washer 13 and in turn on the hardened button 14 positioned 30 within the slider 6. 15 is a suction valve assembly screwthreaded into the body 4 and leading in to the pump chamber 16. 17 is a discharge valve assembly screwthreaded into the body 4.

35 Figures 3 and 4 show pump discharge rates. The abscissae represent degrees rotation of the cam shaft and the ordinates represent the percentage of discharge occurring during the preceding selected number of degrees of cam shaft rotation, each of these degree intervals of rotation being conveniently chosen, as say each five degrees, all such intervals being equal.

It is well known that for all reciprocating plunger pumps the rate of discharge varies from zero to a maximum and again to zero during each delivery period. The discharge obviously is zero

at the beginning and end and occurs at varying rates during equal time intervals in the pumping stroke, reaching a maximum at various positions in the stroke depending upon the type of drive used. In cam driven pumps this variation in rate of discharge, or pump delivery characteristic can be controlled to a considerable extent by the shape of the cam.

When such pumps are used for feeding fuel to the atomizer of a Diesel engine, this variation in 10 the rate of discharge becomes highly important, since it has a pronounced effect upon combustion. Certain type of combustion chambers, for example, operate most satisfactorily with relatively low initial rates of discharge and with the peak 15 obtained well along in the stroke. Other chambers operate best when the initial rates rise rapidly and the peak is reached relatively early in the stroke. Pressure and temperature conditions also require different pump delivery characteristics. It is therefore highly desirable in 20 commercial pumps to arrange to provide for considerable variation in the discharge characteristics.

Such changes in delivery characteristic have 25 heretofore been accomplished by changing the cam or by using only a portion of the drive face of the cam for actual delivery and changing the mechanism which determines the portion of the cam face to be used, thereby obtaining the result 30 by using different portions of the driving face. Both these methods are expensive and cumbersome. In the mechanism which is the subject of this invention the desired result is easily and 35 quickly accomplished by setting the axis of the slider and roller (the cam follower) off center from the center line of the cam shaft. It is easily demonstrated that the amount of this offset causes a marked change in the position of the peak rate of discharge with respect to the total 40 discharge period. Figures 3 and 4 are graphs showing two distinct delivery characteristics obtained by merely shifting the axis of the pump body which carries the cam follower, Figure 3 showing the condition existing when the axis of 45 the pump body is shifted away from the axis of the cam shaft in the direction of rotation of the cam, the condition shown in Figure 1. In this case it will be noted that the maximum rate of discharge occurs early in the stroke, which as explained is desirable for certain engines. To move 50 this maximum rate of discharge toward the latter portion of the stroke, as shown in Figure 4, it is only necessary to shift the pump body toward the axis of the cam shaft against the direc- 55

tion of the rotation of the cam. Thus, this peak rate of discharge may be moved along the degree base line, as shown in the graph, by merely shifting the pump body back and forth. The construction which makes this possible is simply to provide some slots in the body section of the pump and some cap screws or bolts to lock the body when the desired position is reached.

The movement of the pump body above described will produce varying positions of the plunger and cam follower assembly. As the body is moved to the right, as shown in Figure 1, the plunger and cam follower will move downward somewhat toward the cam shaft, acting under the influence of the spring 12. This occurs without materially changing the stroke, although there may be a slight tendency to increase the stroke. With the plunger and pump body moved to the right, the plunger merely reciprocates approximately the same amount, but in a different portion of the barrel. In general this does not appreciably affect the operation of the pump.

The use and operation of the invention are as follows:

The operation of such pumps generally when used on Diesel engines is too well known to need detailed description. A source of oil supply is connected to the inlet valve assembly 15, whereby oil is admitted on the suction stroke of the pump into the chamber 16 and then, upon the discharge stroke, expelled from the chamber 16 through the discharge valve assembly 17 to the atomizing valve in the engine. The cam and cam follower are conventional structures. The particular cam shown has a flat driving face and a long circular eccentric return or suction face. The novelty of the device consists in the ability to shift the pump body with respect to the cam shaft to obtain varying delivery characteristics as already described. Assuming the pump to be placed in operation on an engine and a particular delivery rate to be found unsuited to the specific engine

construction and conditions, it is merely necessary to loosen the cap screws 5 and shift the pump to right or to the left as the particular requirements of the engine indicate is desirable. The body may be locked in an approximate position and the engine again operated and if improvement is noted the pump may be shifted further in the same direction and this process repeated until the optimum is passed and a decrease in performance is observed. The body may be then shifted backward to the point determined as giving the best operation.

Such changes of delivery characteristic are of exceptional importance when changes in fuel are made, even though other engine conditions remain the same. It is therefore highly desirable to be able to vary delivery characteristic in an installed pump without expensive or complicated changes or replacements.

It is of course obvious that this principle may be applied to a wide variety of pump construction and it is in no wise limited to the particular form shown.

A variety of locking devices may be employed, and the shifting of the body may be accomplished by screwthreaded devices such as are used to position electric motors. A calibrated scale may be attached to identify various body positions as best for certain purposes.

I claim:

In a pump, a base member, a pump driving cam shaft supported in said member, a cam on said shaft, a pump body provided with inlet and outlet valves, a plunger reciprocally mounted in said body, a follower positioned to actuate said plunger and to be acted upon directly by the cam, and means for movably mounting said body upon said base for movement at right angles to the axis of the cam shaft, to adjust the axial distance between the center line of the cam shaft and the center line of the follower.

PHILIP LANE SCOTT.
